UNITED STATES PATENT OFFICE.

OSCAR V. PAYNE AND RICHARD GREENLEAF TURNER, OF WORCESTER, MASSACHUSETTS, ASSIGNORS TO CROMPTON & KNOWLES LOOM WORKS, OF WORCESTER, MASSACHUSETTS, A CORPORATION OF MASSACHUSETTS.

GIVE WAY FOR WEFT-REPLENISHING MECHANISM.

Application filed November 15, 1926. Serial No. 148,401.

This invention relates to improvements in giveways or yielding supports for weft replenishing mechanisms more particularly of the multi-color type, and it is the principal object of the invention to simplify these devices to the end that a single resilient device may be made to operate with a pair of supports.

In multi-color weft replenishing mechanisms the bobbins are usually arranged in vertical stacks according to distinctive characteristics, such as size, color, etc. and cradles release the lowermost bobbin of the stack corresponding to the depleted shuttle, so that the bobbins may move to a common transfer position immediately over the shuttle when the lay is in its extreme forward position. A bobbin released by its cradle is guided down the inclined surfaces of yielding supports. It is found that mechanisms of this type operate more satisfactorily when the front giveway yields under a comparatively high resistance and the rear giveway under a comparatively low resistance. For a great many years the front support was made as an integral part of the magazine to insure proper movement of the bobbin into the shuttle, but in recent years the front giveway for the butt of the bobbin has been made yielding under rather high pressure. The reason for this change in construction was brought about by occasional breakages resulting when a bobbin moving from one of the front cells or stacks was caught under the transerrer and pushed downwardly against the integral support. It is an important object of our present invention to provide a pair of bobbin supports or giveways which are held together by a single resilient device applied to the giveways at different distances from their pivots so that the front support yields under relatively high pressure and the rear support under relatively light pressure. In this respect our invention aims to provide a construction similar in purpose to that shown in co-pending application Ser. No. 739,692 filed by Hume and King.

With these and other objects in view which will appear as the description proceeds, our invention resides in the combination and arrangement of parts hereinafter described and set forth in the claims.

In the accompanying drawings wherein

we have shown a convenient embodiment of our invention,

Fig. 1 is a side elevation of a portion of a multi-color weft replenishing mechanism looking from the interior of the loom,

Fig. 2 is a view of a portion of the mechanism shown in Fig. 1 but from the opposite side looking toward the center of the loom, and

Fig. 3 is a vertical section on line 3—3 of Fig. 1.

Referring to the drawings the loom side 10 has mounted thereon the foot 11 of a multi-color replenishing mechanism 12 formed with a plurality of spaced flanges 13 defining vertical compartments or cells 14 in which the bobbins are located as they await transfer. A plurality of vertical slides 15, one for each stack, are provided and are controlled as to their vertical position by a color slide 16 movable longitudinally in timed relation with the box motion at the opposite side of the loom and moved angularly to lift the slide corresponding to the active shuttle at the time of indication of weft exhaustion and to depress the slide when the shuttle giving the indication is about to return under the magazine. The mechanism for imparting this angular movement may include a lever 17 pivoted at 18 to the magazine 12 and having a horizontal arm 19 connected to the color slide by means of a vertical link 20. The depending arm 21 of the lever has an inclined forwardly and upwardly extending surface 22 which cooperates with an indicating plunger 90 of the type set forth in Patent No. 1,372,316 to Ryon. The other features of the mechanism thus far described may also be as set forth in Patent No. 1,030,748. The transerrer arm 23 may be pivoted on a fixed stud 24 and may be as set forth in said patent when the lever 17 is employed or it may be of the usual form when the magazine is made according to said Patent No. 1,030,748.

In carrying our improvements into effect we provide the frame 12 with a pair of studs 30 and 31 located, respectively, in front of and behind the center of the magazine. Stud 30 affords pivotal mounting for support or giveway 32 while support or giveway 33 is mounted on stud 31. Each of said supports may be formed as shown more particularly in Fig. 3 and extends down-

wardly as at 34 and under the lower portion of the frame 12. Each support has preferably integral therewith an inclined bobbin guide 35 lying on the inside magazine, as shown in Fig. 3.

Support or giveway 32 is normally in direct contact with the lower surface 36 of the magazine, but support 33 is provided with an adjustable stop screw 37 which bears normally against surface 38 of the frame. By means of screw 37 the distance between adjacent lower ends of the guides 35 may be controlled.

In order that said supports may be held together yieldingly we provide a tension spring 39 having the left end secured as at 40 to the support 33 and having the right end connected to the support 32 as at 41, as viewed in Fig. 1. The left end of the spring 20 is closer to stud 31 than the right end is to stud 30. The purpose of this arrangement is to cause greater resistance to the forward yielding of support 32 than is offered to the rearward yielding of support 33.

25 In operation when transfer is about to take place the lowermost bobbin in the stack or compartment corresponding to the shuttle to be replenished will be released and the butt of said bobbin will be guided down one 30 or the other of the inclined guides 35 and assume the position indicated at B in Fig. 1. The transerrer arm 23 will then be brought down by mechanism depending upon the type of magazine, and the bobbin will be 35 moved between said supports, the rear support 33 moving slightly to permit the butt of the bobbin to pass, and the support 32 remaining stationary because of the greater pressure exerted thereon by the spring, said 40 forward support guiding the bobbin into the shuttle. If for any reason the bobbin should be caught between the transerrer arm and a guide 35, the latter will yield to avoid breakage.

45 While we have shown our giveways or supports in connection with a magazine having a transerrer which receives a downward movement on every alternate pick of the loom, yet we do not wish to be limited to 50 this construction, as the supports will operate with equal effectiveness irrespective of the manner in which the transerrer arm is depressed or indication of weft exhaustion is given to the magazine.

55 From the foregoing it will be seen that we have provided a single resilient device for holding a pair of yielding bobbin supports in normal position and it will further be seen that by having this resilient device connected to the supports at different distances from their pivots, different degrees of resistance to yielding are offered by the supports.

Having thus described our invention it 60 will be apparent that changes and modifica-

tions may be made therein by those skilled in the art without departing from the spirit and scope of the invention, and we do not wish to be limited to the details herein disclosed but what we claim is:

1. In a weft replenishing mechanism, a pair of movable supports for holding one end of a bobbin in transfer position, means to hold the supports apart a distance less than the diameter of the butt of the bobbin, 75 and a single yielding device connected to both of said supports to hold said supports in normal position and resisting movement of each support away from normal bobbin supporting position, each support being 80 yieldable and the deformation of the device being dependent upon the diameter of the butt of the bobbin and independent of the relative amounts each support moves.

2. In a weft replenishing mechanism, a movable support for the front of the butt of the bobbin, another movable support for the rear of the butt of the bobbin, means to hold the supports apart a distance less than the diameter of the butt of the bobbin, and a 90 single yielding device interposed between and connected to said supports to hold the same in normal bobbin holding position and offering resistance to the motion of each of said supports relatively to the mechanism, 95 each support being yieldable and the deformation of the device being dependent upon the diameter of the butt of the bobbin and independent of the relative amounts each support moves.

3. In a weft replenishing mechanism, a pair of substantially similar bobbin supports each movable relatively to the replenishing mechanism and each having an inclined guide, means to hold the supports apart a 100 distance less than the diameter of the butt of the bobbin, said guides cooperating to support the butt of a bobbin in transfer position, and a single resilient device connected to said supports to hold the same 105 yieldingly in normal position and resisting movement of each of said supports relatively to the replenishing mechanism, each support being yieldable and the deformation of the device being dependent upon the diameter of the butt of the bobbin and independent 110 of the relative amounts each support moves.

4. In a weft replenishing mechanism, a pair of bobbin supports each pivotally connected to the replenishing mechanism at a point above a bobbin when in transfer position, a bobbin guide for each support, the guides serving to hold the butt of a bobbin in transfer position, means to hold the guides apart a distance less than the diameter of the butt of the bobbin, and a resilient device located between said supports to hold the same yieldingly in normal position and resisting movement of each support relatively 115 120 125 130

to the replenishing mechanism, each support being yieldable and the deformation of the device being dependent upon the diameter of the butt of the bobbin and independent of the relative amounts each support moves.

5. In a weft replenishing mechanism, a pair of bobbin supports each pivotally connected to the replenishing mechanism at a point above a bobbin when in transfer position, a bobbin guide for each support, the guides serving to hold the butt of a bobbin in transfer position, means to hold the guides apart a distance less than the diameter of the butt of the bobbin, and a single resilient device located between said supports to hold the same yieldingly in normal position and resisting movement of each support relatively to the replenishing mechanism, said resilient device comprising a tension spring attached to the supports at points below the pivots thereof, each support being yieldable and the deformation of the device being dependent upon the diameter of the butt of the bobbin and independent of the relative amounts each support moves.

6. In a weft replenishing mechanism, a pair of supports for a bobbin in transfer position, and a single yielding device connected to said supports to hold the same yieldingly in normal position and exerting unequal pressures on said supports to cause one of said supports to offer greater resistance to moving relative to the mechanism than is offered by the other support.

35 7. In a weft replenishing mechanism, a pair of supports to hold the butt of a bobbin

in transfer position, means defining a pivotal mounting for each support, and a single yielding device having operative contact with each support to hold the same yieldingly in normal position, said device having contact with the supports at unequal distances from their pivots to cause one of said supports to offer greater resistance to movement relatively to the mechanism than is offered by the other support.

8. In a weft replenishing mechanism, a pair of supports for the butt of the bobbin each pivotally mounted on the mechanism, and a single resilient device connected to the supports to hold the same yieldingly in normal position, the distance between the pivot of one support and the point of attachment of the resilient device to said support being greater than the distance between the pivot of the other support and the point of attachment of the resilient device thereto.

9. In a weft replenishing mechanism, a pair of bobbin supports, pivots therefor carried by the replenishing mechanism and in substantial alignment, and a single resilient device connecting the two supports together to hold the same yieldingly in normal position and resisting relative movement of each support with respect to the mechanism, said resilient device being disposed obliquely with respect to a horizontal line.

In testimony whereof we have hereunto affixed our signatures.

OSCAR V. PAYNE.
